UNITED STATES PATENT OFFICE

106,727

DESIGN FOR A COAT

Morris Hiller, New York, N. Y.

Application July 3, 1937, Serial No. 70,252

Term of patent 3½ years

To all whom it may concern:

Be it known that I, Morris Hiller, a citizen of the United States, residing at 148 West 37th Street, New York, N. Y., have invented a new, original, and ornamental Design for a Coat, of which the following is a specification, reference being had to the accompanying drawing, forming part thereof.

Fig. 1 is a front elevational view of a coat embodying the design, the lower portion of the coat being broken away;

Fig. 2 is a rear elevational view of the coat of Fig. 1 with the coat completed; and

Fig. 3 is a fragmentary side elevational view of the coat of Figs. 1 and 2 illustrating the design of the coat sleeve.

The lines shown on the surface of the sleeves, shoulders, lapels and collar of the coat indicate single raised decorative ridges.

I claim:

The ornamental design for a coat substantially as shown and described.

MORRIS HILLER.
